UNITED STATES PATENT OFFICE.

WILLIAM H. DOBLE, OF QUINCY, MASSACHUSETTS, ASSIGNOR OF ONE-FOURTH TO
PNEUMATIC SCALE CORPORATION, LIMITED, OF QUINCY, MASSACHUSETTS, A COR-
PORATION OF MAINE.

PANEL FOR BOXES.

1,093,548.

Specification of Letters Patent. Patented Apr. 14, 1914.

Application filed March 7, 1913. Serial No. 752,592.

To all whom it may concern:

Be it known that I, WILLIAM H. DOBLE, a citizen of the United States, residing at Quincy, county of Norfolk, State of Massachusetts, have invented a certain new and useful Improvement in Panels for Boxes, of which the following is a specification, reference being had therein to the accompanying drawings.

10 The invention relates to a box panel having an inner and an outer wall spaced apart from each other, being specially intended for a box in which the panel forming one side of the box is hinged to a panel forming another side.

By the term "panel" I mean any one of the four sides or the top or the bottom of the box.

20 The invention is especially adapted for a metal box although it will be obvious that other material may be employed.

The object of the invention is to produce a smooth, finished appearance to the edges of the panels, as well as to stiffen them and 25 to close the space between the walls against foreign matter getting lodged between the walls.

30 The invention will be fully understood from the following description taken in connection with the accompanying drawings, and the novel features will be pointed out and clearly defined in the claims at the close of the specification.

In the drawings,—Figure 1 is a plan view 35 of a box panel embodying the invention, which for convenience we may say is for a cover. Fig. 2 is an edge view of the panel shown in Fig. 1, and showing portions of two panels connected therewith, which if 40 Fig. 1 represents the cover will be the front and back panels. Fig. 3 is a section on line 3—3 of Fig. 1. Fig. 4 is a section on line 4—4 of Fig. 1. Fig. 5 is a section, enlarged, on line 5—5 of Fig. 1. Fig. 6 is a section, 45 enlarged, on line 6—6 of Fig. 1.

Referring now to the drawings, the body of the panel A comprises an inner plate 1, an outer plate 2 and preferably a corrugated stiffening and strengthening plate 3. This 50 corrugated plate has a zigzag appearance in cross section, contacting alternately with the inner and outer walls. The general form

of construction of the corrugated plate is, shown in Patent No. 941,018, dated Nov. 23, 1903, granted on the application of Doble and Wheaton. It is rather difficult to make the corrugated plate with the end flange such that it will form a flush, smooth closure for the edge space between the inner and outer walls because of more or less variation in the exact size and also variation due to expansion and contraction, and other causes. It is therefore preferable to make the corrugated plate of somewhat less width and length than the panel itself and to insert a closure member into the said edge space to 60 make the edge look smooth and trim. The present invention relates to the closure.

If the box is of the type in which one or more of the panels are hinged to one or more 70 of the adjacent panels, the closure member may be formed to also furnish the knuckles for the hinge. The form of panel shown in the drawings is of this latter type and illustrates two edges adapted to be hinged to 75 two other panels C, D and unattached to the other two adjacent panels (not shown). For instance, if the panel be used as the cover it could have the front and rear 80 hinged to other panels and the two ends un-hinged. If hinged as above one of the hinge pins 10 should be removable endwise to allow of turning the cover on the other hinge.

The unhinged edges are closed by what I 85 term a channel piece B, which, if the box is of metal, is a strip of metal bent or cast in U-form, as shown in Fig. 3, having the two parallel leg portions 4, 4 and an intermediate or head portion 5, the legs being 90 spaced apart just enough to make a snug fit when the channel piece is inserted between the inner and outer plates. The corrugated plate should stop short of the edge far enough to surely allow the channel plate 95 to be inserted a sufficient distance to bring the intermediate portion or head 4 of the channel piece flush with the edges of the inner and outer plates 1, 2. The channel piece should be secured firmly in this position. The preferable method is by welding, as this leaves a smoother surface than if riveted.

The hinge edges of the panel will be

closed by a closure member E made of a sheet blanked out and bent to form a series of knuckle portions 6, with parallel leg portions 7, and preferably a cross flange portion 8 at the inner end to aid in giving additional stiffness on account of possible strain on the hinges more than on the unhinged edges. The intermediate portions between the knuckles 6 have instead of the 10 knuckles a flat cross flange 9 which forms a smooth closure for the portions of the edge between the knuckles in the same manner as the head 5 of the channel piece B closes the space at the edges of the unhinged sides.

15 The entire closure piece E including the knuckles 6, legs 7, cross flanges 8 and 9 is all one integral piece made from a sheet die cut and bent to the proper shape. The flange 8 may extend continuously the entire 20 length of the closure piece. The flanges 9 are interrupted by the knuckle portions and consist of a series of short flanges each of a length equal to the spaces between the knuckles. The channel pieces should be 25 mitered at their ends to form a smooth joint, as shown in dotted lines in Fig. 1. It will thus be seen that the same member serves both as a hinge and as a closure for the edge space between the walls and it not only gives 30 a finished appearance to the edge but it stiffens and strengthens the panel.

By making the hinge as a separate piece from the inner or outer wall plate of the panel, the hinge can be made of heavier 35 stock than is required for the sheets of metal which form the inner and outer wall plates, thus gaining stiffness at the hinge while not materially increasing the weight of the panel.

40 What I claim is:

1. A box panel comprising an inner and an outer wall plate spaced apart from each other, and a closure member for the space between said plates at one or more of the 45 edges throughout the length thereof consisting of an integral channel piece having two parallel leg portions and a head portion, all of which fit between the two plates, said head portion bridging the space between the edges throughout the length thereof and being flush with said edges:

2. A box panel comprising an inner and an outer wall plate spaced apart from each other and a closure member consisting of 55 an integral channel piece extending the entire length of the edges of the plates and having two parallel leg portions which fit between the two plates, a plurality of knuckle portions for a hinge which project 60 beyond the edge of the panel, with spaces between the knuckles, and flange portions between the knuckle portions which bridge the space between the inner and outer walls

at the edges of said walls, said knuckles and intermediate flange portions being integral 65 with each other.

3. A box panel comprising an inner and an outer wall plate spaced apart from each other, closure members for some of the spaces between said plates, at the edges thereof, each consisting of a channel piece having two parallel leg portions and a continuous head portion all of which fit between the two wall plates, said head portion bridging the space between the said wall 75 plates throughout the length and being flush with the edges thereof, and channel pieces at other edges of the plates composing said panel having two parallel leg portions which fit between the two plates and a plurality of 80 knuckle portions to receive a hinge pin with intervals between the knuckles, and bridge portions for the intervals between said knuckles flush with the edges of the wall plates, said leg portions, knuckles, and intermediate bridge portions all being integral 85 with each other.

4. A box panel comprising an inner and an outer wall plate spaced apart from each other and a closure member for the space 90 between said plates at their edges consisting of a channel piece having two parallel leg portions which extend into the space between the two plates, a plurality of knuckle portions for a hinge integral with said leg 95 portions, said knuckle portions having intervals between them and flange portions integral with said knuckle portions which bridge the space between the inner and outer walls in the intervals between said knuckle 100 portions.

5. A box panel comprising an inner and an outer wall plate spaced apart from each other and a closure member for the space between said plates at their edges consisting 105 of a channel piece having two parallel leg portions which extend into the space between the two plates, a plurality of knuckle portions for a hinge integral with said leg portions, said knuckle portions having intervals between them, flange portions between the knuckle portions which bridge the space between the inner and outer wall plates at the outer edge, and a flange portion 110 extending from the inner end of one of said leg portions across the intervening space between the walls to the other leg portion.

6. In combination with a box panel comprising an inner and an outer wall plate 120 spaced apart from each other, a corrugated stiffening plate inclosed between said inner and outer plates and contacting alternately with the inner faces of said wall plates, said corrugated plate stopping somewhat short 125 of the edges of said inner and outer plates,

and a closure member for the space between said inner and outer plates at their edges, consisting of a channel piece having two parallel leg portions which extend into the space between the said inner and outer plates and engage the inner faces thereof respectively, said channel piece having a bridge portion which connects said parallel leg portions on the outer edge and extends

across the space between the inner and outer 10 wall plates.

In testimony whereof I affix my signature, in presence of two witnesses,

WILLIAM H. DOBLE.
